UNITED STATES PATENT OFFICE.

EDWARD ALFRED GRAHAM, OF BROCKLEY, LONDON, ENGLAND.

LOUD-SPEAKING TELEPHONIC APPARATUS.

Application filed June 30, 1924. Serial No. 723,383.

To all whom it may concern:

Be it known that I, EDWARD ALFRED GRAHAM, a subject of the King of Great Britain and Ireland, residing at Brockley, in the 5 county of London, England, have invented Improvements in or Relating to Loud-Speaking Telephonic Apparatus, of which the following is a specification.

This invention has reference to portable 10 loud speaking telephonic apparatus and it has for its object to provide apparatus of this type that can be easily transported from place to place and conveniently used in the open air in connection with wireless receiving apparatus, as for instance by picnic, boating and other parties, clubs and the like.

For this purpose, portable loud speaking 20 telephonic apparatus according to the invention, comprises a case having one or more movable sides or doors and it may be a movable top or cover, and a loud speaking telephone comprising a telephonic receiver and a sound conduit or resonating box or 25 chamber the mouth or sound emission aperture of which is adapted completely to occupy the opening, or one of the openings, normally closed by a movable side or door, when the loud speaking telephone is not in 30 use.

The case may be provided with supporting 35 means capable of being attached to and detached from the case, or hinged or jointed thereto, and whereby the case with loud speaking telephone can conveniently be erected and supported in position for use and which can be removed from, or folded up against the case for storage or transport.

40 The loud speaking telephone may be adapted to slide in the case, so that it can be withdrawn, wholly or partly, through the opening at the front of the case, or through an opening at the back of the case, to permit 45 of adjustment of the telephonic receiver. Or the case may be provided with a hinged or removable top or cover to admit of the combined telephonic receiver and the attached sound conduit or resonating box or 50 chamber (hereinafter called the sound conduit) being readily inserted in the case from above and of the telephonic receiver being afterwards readily adjusted, when desired, without removing it and the sound conduit 55 from the case. Or, for these purposes, the case may be provided with a hinged or re-

movable side wall or door. Or, adjustment of the telephonic receiver may be effected through an aperture in one of the side walls, or the top of the case. 60

The end cover of the case opposite the sound emission end of the sound conduit may be hinged to the top of the case so that it can be turned upward and, if desired, folded backward against the top of the case. 65 Or it may be hinged to one side of the case, so that it can be turned outward and folded backward against the said side of the case. The case is provided at one side, or it may be at the top, with a handle by which it can 70 conveniently be carried.

In constructions of apparatus of the kind referred to, the case, which may be covered with leather, after the manner in which cameras are so covered, and be of rectangular shape, may be adapted to admit of its being conveniently supported in position for use. For this purpose it may be provided on its underside with a screw threaded socket to which a folding tripod or other 75 stand can be attached. Such tripod or other stand, when not in use, can be folded up and placed within the case, it may be after its folded parts have been secured together, as by a clip device, or enclosed within a 80 tubular sheath.

In the accompanying drawings, Fig. 1 is a perspective external view of one construction of loud speaking telephonic apparatus according to the invention, complete and 90 ready for transport. Fig. 2 is a plan view of the same in the position it will usually occupy whilst in use, one side of the case of such apparatus being opened to show the internal parts. Fig. 3 is a perspective view 95 showing the apparatus supported by a tripod in position for use. Fig. 4 is a cross section of the case of the apparatus with the loud speaking telephone removed. Fig. 5 is a perspective view, to a larger scale than Figs. 100 1, 2 or 3, of the loud speaking telephone used in apparatus as shown in Figs. 1, 2 and 3 and Fig. 6 is a part sectional plan of such loud speaking telephone. Figs. 7 and 8 are underside views showing modified constructions. 105

Referring to Figs. 1 to 6, the case *a*, which enclosed a loud speaking telephone, is provided with a movable front end wall *b* jointed by hinges *b*¹ to one of the side walls 110 of the case and arranged normally to close the enlarged end *c* of the sound conduit of

a loud speaking telephone enclosed within the case, a movable side wall *d*, hinged at *d*¹ to the side wall of the case to which the end wall *b* is hinged, a screw-threaded socket *e* in the side wall of the case opposite to the wall *d* and designed to receive a screw-threaded stem *f*¹ carried by the upper end or head *f*² of a tripod support *f* and a handle *g* attached to that side wall of the case to which the front wall *b* and side wall *d* are hinged and by means of which the case and its contents can conveniently be carried. The arrangement is such that when required for use the case is arranged with its hinged side wall *d* uppermost and the side wall with the screw-threaded socket *e* lowermost, so that the front wall *b* can be turned about a vertical axis located at one side of the case, as shown in Figs. 2 and 3.

The sound conduit of the loud speaking telephone may advantageously be of U shape (see Figs. 2, 5 and 6) and be arranged horizontally within the case *a*, its outlet end terminating in the flared or trumpet shaped open end portion *c* that is preferably of rectangular shape in cross section as shown, and fits at its extreme front end, the front open end of the case, whilst its other and smaller end portion, which extends in a forward direction but not to so great an extent as the larger open end, is bent upward and adapted to carry at its upper end, the telephonic receiver *h*, the diaphragm of which is arranged to be in a horizontal plane when the apparatus is in use (Figs. 2 and 3). The intermediate portion of the sound conduit is of U shape.

According to the construction shown in Figs. 2, 5 and 6, the flared or trumpet-shaped outlet end portion *c* of the sound conduit is of rectangular cross section and made of wood. The intermediate U shaped portion *c*¹ of the sound conduit is of metal and of gradually increasing circular cross section area from its inlet end to its outlet end where it is provided with an enlarged rectangular portion *c*² fitting over the inlet end of the flared or trumpet shaped portion *c* of the said conduit. The upwardly bent inlet end portion *c*³ of the sound conduit, carrying the telephonic receiver *h*, is of circular cross section. The front outlet, intermediate and inlet portions, *c*, *c*¹ and *c*³ of the sound conduit are or may advantageously be jointed together with the aid of interposed material of a non-sonorous character, as for instance rubber, so that the several portions shall be acoustically insulated from one another. The connection of the horizontally disposed telephonic receiver *h* to the upper end of the upwardly bent inlet portion *c*³ of the sound conduit is or may be effected by the aid of a socket or hollow plug, preferably of rubber or equivalent non-sonorous material, carried by the tele-

phonic receiver and fitting over or into the said upper end of the sound conduit. Fig. 5 shows sockets *i* and *i*¹ of rubber or like sound insulating material connecting the ends of the inlet portion *c*³ of the sound conduit to the portion *c*¹ of that conduit, and the telephone receiver *h* respectively, whilst Fig. 6 shows a bush *i*² of such insulating material, arranged between the plug and socketed ends of the portions *c* and *c*¹.

In some cases, the said upwardly bent inlet end portion *c*³ of the sound conduit to which the telephonic receiver *h* is attached, may be formed as a substantial tubular element of non-sonorous material, as for instance rubber of medium hardness and rigidity.

The telephonic receiver *h* may be provided with any known or suitable means whereby its electro-magnetic system can be readily adjusted relatively to its diaphragm. Conveniently, the adjustment may be effected by a screw *k*, and nut *k*¹, it may be against the action of a spring, in the manner set forth in the specification of former British Letters Patent No. 15369 of 1915 granted to me. Or the adjustment may be effected by a screw or cam and a lever in the manner set forth in the specification of another application for Letters Patent Serial No. 712357 filed by me.

The loud speaking telephone hereinbefore described may be acoustically insulated as a whole from the case *a* in which it is disposed, as by the interposition of washers or buffers *m*, (Fig. 4) of non-sonorous material, such for example as india rubber or felt, and be fixed in place by suitable clips or fastening devices, one of which is shown at *n* in Fig. 4.

By the construction described, a loud speaking telephone having a relatively long and expanding sound conduit can be arranged within a case *a* of comparatively small dimensions.

The twin conductors *o* (Fig. 3) connected to the terminals *h*¹ of the telephonic receiver *h* can, after use of the apparatus has been discontinued, be coiled up and placed within the case *a* for easy and convenient transport, or they may be wound upon a spring controlled drum mounted within the case.

To enable the tripod support *f*, when shortened and folded up-to be conveniently stored within the case *a* the latter is provided with a socket like holder *r* for the reception of the head *f*² of the tripod support with its screw threaded stem *f*¹ and with a bracket *s* to carry the shortened legs of the tripod support, a movable spring clip *t* serving to hold the legs firmly in place.

The bottom of the case *a* instead of being provided with a screw-threaded socket *e* for the attachment of a tripod support as de-

scribed, may, as shown in Fig. 7, be provided with a centrally arranged boss *u* to which three radially arranged telescopic legs *f* are hinged or jointed in such a manner that they can be opened out to form a tripod stand to support the case *a* in position for use, or can be folded up close against the bottom of the case to which they may conveniently be held, as by spring clips 10 *v*, when the apparatus is not required for use, and for storage or transport.

Or, according to the further modified construction shown in Fig. 8, two legs *f* may be hinged to the bottom of the case *a* near 15 to the corner portions thereof at one end of the case and a third leg *f* be hinged to the bottom of the case near to the opposite end of the case and centrally thereof, in such manner that the three legs can be turned 20 up close against the bottom of the case and held in position, as by spring clips *v*, for storage or transport.

What I claim is:—

1. Portable loud speaking telephonic apparatus comprising a case having an opening therein and a movable wall normally closing said opening, a loud speaking telephone comprising a telephonic receiver and a sound conduit, wholly located within said 25 case, the sound conduit having a flared out-

let end occupying the opening in said case, collapsible supporting means adapted to hold said case above the ground in position for use and coacting detachable screw threaded connecting means carried by the 30 case and collapsible supporting means, substantially as described.

2. Portable loud speaking telephonic apparatus comprising a case one end wall and one side wall of which is hinged thereto, a 40 loud speaking telephone comprising a telephonic receiver and a bent sound conduit, wholly located within said case, the outlet end of said sound conduit being of flaring shape and fitting the end of the case provided with the hinged end wall and the inlet end of said sound conduit being bent 45 towards the said hinged side wall and having the telephonic receiver applied thereto.

3. A loud speaking telephone according 50 to claim 1, in which the outlet or sound emission end portion of the sound conduit has one side wall flat and vertical, the opposite side wall convex and vertical, the top wall convex and extending horizontally and 55 the bottom wall flat and horizontal.

Signed at London, England, this 20th day of June, 1924.

EDWARD ALFRED GRAHAM.
